UNITED STATES PATENT OFFICE.

JOHN F. JONES, OF CHICAGO, ILLINOIS.

AUTOMATIC FLOOR INDICATOR FOR PASSENGER ELEVATORS.

Application filed February 20, 1924. Serial No. 694,091.

To all whom it may concern:

Be it known that I, JOHN F. JONES, a citizen of the United States, residing at Chicago, in the county of Cook and State of Illinois, have invented certain new and useful Improvements in Automatic Floor Indicators for Passenger Elevators; and I do declare the following to be a full, clear, and exact description of the invention, such as will enable others skilled in the art to which it appertains to make and use the same.

My invention aims to provide a simple, yet an effective device adapted to be carried by the car or cage of a passenger elevator, in full view of the passengers, so that by simply looking at the device, the floor position of the elevator can be seen, thus effectively overcoming a great deal of confusion and inconvenience which ordinarily results, particularly in the elevators of rather tall buildings.

With the foregoing in view, the invention resides in the novel subject matter hereinabove described and claimed, the description being supplemented by the accompanying drawing.

Figure 1 is a vertical sectional view through a portion of an elevator shaft, and a number of its doors, showing the elevator car in elevation, equipped with the indicating means.

Figure 2 is a sectional view as indicated by line 2-2 of Fig. 1, diagrammatically illustrating the electrical means for illuminating the floor indicator.

Figure 3 is an enlarged vertical sectional view as indicated by line 3-3 of Fig. 1, showing the floor indicator in elevation.

Figures 4 and 5 are transverse sectional views as indicated by lines 4-4 and 5-5 of Fig. 3.

Figure 6 is a longitudinal, substantially vertical section through the indicator, as indicated by line 6-6 of Fig. 4.

Figure 7 is a horizontal sectional view on line 7-7 of Fig. 6.

Figures 8 and 9 are elevations partly in section, showing the manner in which the elevator doors control circuit-closing switches for the illuminating light of the floor indicator.

In the drawing above briefly described, I have illustrated a passenger elevator car C within a shaft S which is provided with the usual doors D at the several floors F.

Mounted within the cage or car C, at a point preferably over the door thereof, I have shown a casing 1 having a view opening 2, and if desired, this casing may set at 60 an angle as shown in Figs. 2 to 5, in order that the floor numbers which are successively displayed at the opening 2, may be more readily visible to persons standing near the door. In the ends of the casing 1, 65 I have shown rollers 3 and 4 around which a belt 5 is trained, said belt having floor numbers as indicated in Fig. 3, to be successively displayed at the view opening 2.

Any suitable provision may be made for 70 driving the belt 5 in synchronism with the movement of the car C. In the present disclosure, a relatively large bevel gear 6 is secured upon the shaft of the roller 4 and meshes with a small bevel pinion 7, this 75 pinion being secured to the inner end of a horizontal shaft 8 which passes to the exterior of the car C and is provided with a rather large wheel 9 which is by preference formed with a peripheral groove. A cable 80 10 is passed one or more times around the wheel 9, as indicated at 11, and the ends of this cable are adapted to be anchored at the ends of the shaft S as indicated at 10' in Fig. 1. Thus, as the car C travels upwardly 85 and downwardly, the roller 4 will be driven to properly move the belt 5 in timed relation with the car travel, so as to properly present the floor numbers at the opening 2.

Within the casing 1, behind the belt 5 and 90 the view opening 2, I have illustrated an electric light 12 for illuminating the number at the opening 2 whenever the door D at any floor is opened. For purposes of better representation, this light is shown in Fig. 2, 95 below the casing 1 and this figure diagrammatically illustrates one system of wiring which may be used in connection with switches at the several floors, controlled by the doors D. In the construction shown, 100 each switch includes a casing 13 mounted in the elevator shaft at the upper end of a door D, said casing containing a stationary contact 14 with which a movable switch member 15 co-acts, said switch member having a 105 spring 16 for closing it, but being also provided with a control member 17 extending to the exterior of the casing 13 in position to be struck by the door D, or one section of the latter, if it be of the vertically divided 110 type. As long as the door D is closed, it holds the control member 17 in position to

retain the switch 15 in its open position as shown in Figs. 2 and 8, but as soon as the door starts open, the spring 16 moves said switch member to closed position as illustrated in Fig. 9, thus automatically illuminating the light 12 and attracting the attention of the passengers to the number of the floor at which the car is stopping.

Preferably used in connection with the 10 features above described, is a translucent colored glass panel 18, interposed between the light 12 and the belt 5, said panel being preferably of red glass so as to distinctively illuminate the floor numbers as they are successively presented.

It will be seen from the foregoing that a simple and inexpensive device has been provided for carrying out the objects of the invention, but I wish it understood that the 20 present disclosure is principally for illustrative purposes and that within the scope

of the invention as claimed, it may be embodied in numerous other forms.

I claim:

A floor indicator comprising a casing having a view opening and adapted to be carried by an elevator car, a belt in said casing having floor numbers adapted to be successively presented at said view opening, rollers in said casing mounting said belt, a shaft 25 connected operatively with at least one of said rollers, a wheel on said shaft at the exterior of the casing, and a cable adapted to be passed around said wheel, said cable being of a length to extend substantially 30 throughout the length of an elevator shaft and the ends of said cable being adapted for anchorage at the ends of the shaft.

In testimony whereof I have hereunto affixed my signature.

JOHN F. JONES.
